BUILDING CONSTRUCTION

Malcolm Wheeler-Nicholson, Great Neck, N. Y.

Application September 2, 1949, Serial No. 113,725

6 Claims. (Cl. 72—1)

The present invention relates to building constructions and building methods applicable to a wide variety of buildings, including houses, apartments, commercial buildings, agricultural buildings and military buildings.

In the buildings trade, it is well known to use building blocks made of a variety of materials. These possess the common characteristics that (a) they are made of materials of such strength as to enable them to carry the weight of the walls and the roof, (b) they are joined together by ordinary flat surface mortar joints with the weakness that such joints imply and (c) their use generally requires the addition of insulating materials, the erection of studding, the use of wall board, etc., thus adding to the time, labor and costs of the building. Further cost is added by the necessity of using different materials for inner walls and partitions, with extensive and expensive carpenter work in the erection of wooden studding, the nailing on of plaster base or wall board, the cutting of doors and windows, etc.

An effort to reduce these costs has resulted in the manufacture of pre-fabricated housing, either of wood, metal or other material. Certain economies are effected by this method, for example by the factory pre-cutting of lumber or stamping of metal to required dimensions, pre-fitting of door and window casings and the pre-fabrication of studding, joists, insulating material and other parts of the structure. However, these pre-fabricated houses suffer from several disadvantages. Their cost and popularity have never been such as to provide a sufficient backlog of orders to permit continuous assembly-line production with its attendant economies. This results in high cost which is increased by the necessity of using skilled labor for assembling and erecting the building after the material has been transported to the site. Pre-fabrication also inherently results in the limitation of architectural design to a minimum number of models. This leads to inflexibility, rigidity and monotony of design. In an effort to cut costs, some of the pre-fabricated houses are cheaply built, so that they soon fall into disrepair.

It is an object of the present invention to overcome these disadvantages and to provide a novel type of construction which is comparable to brick or stone construction in durability, yet is less expensive than either conventional construction or pre-fabrication, while at the same time permitting unlimited scope in architectural design.

In accordance with the invention, a building of any desired shape, size and design is built up of pre-formed elements or panels which fit together to form walls, partitions and other portions of the building. These panels also serve as forms for a poured concrete frame or skeleton which is cast in place after the panels are assembled and not only locks the panels together but also serves as a strong structural framework which takes the load of the walls, ceiling and roof and any upper stories. These panels and the manner in which they are used in the building construction are quite different from the

2

blocks heretofore employed. The construction in accordance with the invention permits wider choice of materials by freeing the panels of the necessity of carrying the weight of the walls and roof, strengthens the jointure of the panels with one another and makes such strengthening an integral element in strengthening the overall design of the building, takes advantage of a wider choice of materials and design in the panels to make the panels self-insulating both by reason of the materials used and the design, thus obviating the use of studding and other additional insulating materials, makes possible the construction of a building with relatively unskilled labour and without need of cranes or other heavy machinery and employs the advantages and the economy of factory pre-fabrication by forming the basic panels with mass production methods. The design of the panels in combination with the engineering principles embodied in their use in erecting a building permits a choice of material that not only makes them self-insulating without the use of interior studding, wall board and insulating materials, other than an exterior coating of cement stucco and an interior coating of plaster, but, in addition, gives the structure durability superior to standard frame construction and comparable to brick and stone construction possessing qualities of fire resistance, sound insulation, heat transfer quotients, moisture-vapor absorption resistance, vermin, termite and other insect resistance and fungus and rust-proof qualities meeting all standard tests for such requirements. In addition, the structure has a resistance to hurricane winds and earthquake shocks superior to that of present types of buildings.

A further object of the present invention is to provide a new type of building construction in which a variety of buildings can be constructed from a relatively small number of basic building units. This makes possible greater economy of production since mass production methods can be used more effectively, tooling and machinery costs are lower and inventory and storage expenses are reduced. The construction is applicable not only to outside walls but also to interior walls and partitions which, in accordance with the invention, constitute an integral part of the building structure.

Other objects and advantages of the invention will become apparent from the following description and claims, in conjunction with the accompanying drawings which illustrate, by way of example, a preferred form of the invention.

In the drawings:

Figure 1 is a perspective view of a basic element or panel in accordance with the invention, portions being broken away to show the internal construction.

Figure 2 is a perspective view, partially in section, showing how reinforcing bars for the poured concrete skeleton or foundation are positioned in channels or troughs provided in the edges of the panel and serving as forms for the concrete framework.

Figures 3 and 4 are perspective views illustrating how the basic panel is divided into sections for easy handling, Figure 3 showing a top section and Figure 4 an intermediate or lower section.

Figure 5 is a fragmentary horizontal section on a larger scale taken across the joints between two panels.

Figure 6 is an exploded perspective view showing the two halves of a panel section before they are united.

Figure 7 is a perspective view of a corner panel.

Figure 8 is a schematic plan on a smaller scale showing how the corner panel of Figure 7 is used in making the corner of a building.

Figure 9 is a perspective view of a pair of window panels.

Figure 10 is a perspective view of a pair of door panels. Figure 11 is an exploded perspective view showing how

the side panels, corner panels, door panels and window panels are assembled on the building foundation.

Figures 12 and 13 are perspective views of tongues or inserts with which the foundation is provided.

Figure 14 is a vertical section of a typical two-story building in accordance with the invention, taken approximately on the line 14—14 of Figure 17.

Figures 15 and 16 are enlargements of portions of Figure 14.

Figure 17 is a vertical section taken on the line 17—17 in Figure 14.

In accordance with the invention, a building of any desired size and shape is quickly and economically built by assembling on a suitable foundation the required number of building elements selected from a relatively small number of basic elements which have the dual purpose of serving as permanent parts of the building, constituting both inner and outer walls, and also serving as complete forms for a poured concrete structural framework or skeleton which is kept in place after the building elements are assembled and takes the major portion of the structural loads of the building.

In the construction illustrated by way of example in the drawings, the basic building element includes basic wall panels B (Figures 1 and 11), basic corner panels C (Figures 7 and 11), door panels D (Figures 10 and 11) and window panels W (Figures 9 and 11).

As the elements B, C, D and W are not required to take any substantial structural load—such load being taken by the poured concrete skeleton or framework—they are preferably made of material selected for light weight and good heat insulating properties while having a moderate amount of structural strength. It has been found highly satisfactory to mold such units of a composition consisting of wood shreds or shavings, or similar vegetable or mineral fibrous material, and a suitable bonding medium, such as plastic or Portland cement. When wood shavings are used, it is preferable to have them relatively long and narrow, for example two to six inches long and $\frac{1}{8}$ to $\frac{3}{8}$ inch wide, rather than in the form of sawdust or chips. For example, equal weight of dry wood shavings and dry Portland cement are combined with enough water to make a plastic mass which is molded to the desired shape with only enough pressure to make it coherent and give it the desired density while leaving a substantial volume of voids in the molded panel. The presence of these voids enhances the insulating properties of the material. Prior to incorporation in the unit, the wood shavings are preferably impregnated by soaking them in a mineral solution to make them resistant to fire, insects, water absorption and decay.

The basic side panel or wall panel B (Figure 1) has a length or height equal approximately to the ceiling height of the building and a width which is less than the height and preferably from $\frac{1}{4}$ to $\frac{1}{2}$ of the height. For example, the panels for use in constructing a residence may be nine feet high and three feet wide. The thickness of the panel is substantially equal to the desired thickness of the finished wall since, in accordance with the invention, it is not necessary to use studding, furring or other auxiliary construction. The panels for a one or two story house may, for example, be eight to twelve inches thick.

As illustrated in Figure 1, the panel is of integral, or one-piece, construction comprising an outer wall portion 1, an inner wall portion 2, peripheral web portions 3 and transverse web portions 4. The bottom edge of the panel is formed with a continuous groove 5 and each of the vertical side edges is provided with a channel 6. While the channel 6 is shown as being semi-circular in cross-section (Figures 1 and 5), it will be understood that the channels may alternatively be triangular, rectangular, hexagonal or other desired polygonal shape, as well as oval or other shape not a true circle. The term "semi-polygonal" is used in the description and claims in a broad sense, to include all of these possibilities. The

channels 6 are of relatively large diameter in proportion to the thickness of the panel while still leaving edges 7 of sufficient strength to avoid their being easily broken in handling. For example, in a panel ten inches thick, the channels 6 may be six inches in diameter leaving each of the edges 7 two inches thick.

At the upper edge of the panel B, there is provided a trough 8 which is preferably of approximately the same width as the channels 6 and substantially greater depth. For example, in a 3 x 9 foot panel ten inches thick, the trough 8 may be six inches wide and ten to twelve inches deep. A continuation of the outer wall portion 1 forms a flange 11 on the outside of the trough 8, while a continuation of the inner wall portion 2 forms an inner flange 12. The inner flange 12 is provided with one or more notches 13 while the outer flanges 11 are provided either with similar notches or with score lines 14 so that notches can easily be formed merely by knocking out the scored material. The notches formed by the score lines 14 are offset from the notches 13 by a distance equal to the width of the notches so that the right hand side of each notch 14 (Figure 1) is in the same plane as the left hand side of the opposite notch 13.

The notches 13 and 14 do not extend to the full depth of the trough 8. For example, if the trough is twelve inches deep, the notches will have a depth of approximately six inches. Moreover, as will appear below, the notches 13 and 14 are not necessarily of the same depth.

The panels B are preferably of hollow construction, as illustrated in Figure 1, a plurality of hermetically sealed cavities 10 being provided between the spaced inner and outer wall portions 1 and 2. These cavities are bounded by the peripheral and transverse web portions 3 and 4 which are integral with the inner and outer wall portions so that the cavities are completely sealed against the entry of moisture. The relatively thin inner and outer wall portions 1 and 2 are reinforced by the transverse web portions 4 the spacing of which can be varied in accordance with the strength requirements. The interior of the panel may be divided into three cavities by two webs 4 as illustrated in Fig. 1. For the sake of clarity only one such web 4 is shown in this figure.

Instead of being in one piece, as shown in Figure 1, the panels can be made in a plurality of sections for greater ease of handling. As illustrated in Figures 3, 4 and 14, each of the basic panels B comprises a top section T and two lower sections L. The lines of division of the panels are along the transverse webs 4 so that each of the sections contains one or more sealed cavities 10. The lower edge of the top section T is provided with a groove 15 which is similar to the bottom groove 5 (Figure 1). Each of the lower panels L is provided at its upper edge with a corresponding tongue 16 so that the panel sections fit together with a tongue and groove joint assuring correct alignment and preventing relative lateral displacement. Except for being divided into a plurality of superposed sections, the panels are the same as described above and corresponding parts are designated by the same reference numerals. In the embodiment illustrated in the drawings, two of the lower sections L and one top section T together form a complete panel B.

To provide a still stronger construction, for example in buildings that are subject to stresses due to settling or in areas subject to earthquakes, hurricanes or tornadoes, the panels are reinforced by woven wire, expanded or perforated metal, or other mesh or foraminous material 17 which, for convenience, is herein referred to as metal mesh. (See Figures 3 and 4.) The metal mesh 17 is continuous in each panel or section and is preferably embedded in the material in approximately the medial plane of the panel. It extends out into the side channels 6 and the top trough 8 and in the lower panel section L it extends up into the tongue 16. To simplify the drawings, the metal mesh has been omitted from certain figures but it will be understood that, where

greater strength is desired, it is preferably incorporated in like manner in all of the panels.

Figure 6 illustrates how a panel section L is formed with a closed cavity 10 and with the metal mesh 17 embedded in the material of the section. The section is first molded in two halves L1 and L2 in complementary molds. When the cement has hardened sufficiently for the molded material to retain its shape but before it has completely set, the two halves are pressed together with the metal mesh 17 between them and pressure is maintained until the material has hardened. The metal mesh being embedded partly in one half and partly in the other half of the section assists in binding the two halves together to form an integral section.

The corner panels C are essentially the same as the side panels B with the exceptions pointed out below. The top section of a corner panel C is illustrated in Figure 7 where corresponding parts are designated by the same reference numerals as in the foregoing figures. One of the vertical edges of the corner panel is provided with a channel 6, as described above, while the opposite edge 18 intersects, or merges into, the adjacent portion of the outer wall portion 1 of the panel to form an outside corner 19 which is shown substantially square (Figure 18) but can be beveled or rounded if desired. On the inner face of the panel, spaced from the corner wall 18, there is provided a channel 6C which corresponds in cross-section to the channel 6. The spacing of the channel 6C from the wall portion 18 is such as to provide a lip or edge 7C which is the same thickness as the edge portions 7 and is in the same plane as the inner wall portion 2. The metal mesh 17 is bent to approximately 90 degrees, as indicated at 21, so as to project out into the channel 6C as well as in the channel 6 at the opposite edge of the panel. While Figure 7 illustrates only the top section of a corner panel, it will be understood that a one-piece corner panel corresponding to the basic panel shown in Figure 1 can be made in like manner.

Fig. 8 illustrates how a corner panel C is used in combination with basic panels B to form the corner of a building. A corner turning in the opposite direction is formed by placing another basic panel in the position shown for panel C and then placing a corner panel C with its channel 6C in registry with the channel 6 of the last mentioned basic panel. The same corner section can hence be used to make either a right hand or a left hand corner or an inside or outside corner while keeping the panels right side up in all instances.

The door panels D (Figure 10) are formed in pairs, the individual panels being designated D1 and D2, respectively. Except for each of the panels being formed to provide one half of a door opening 22, the door panels D are essentially the same as the basic panel B (Figure 1) and corresponding parts are designated by the same reference numerals. By reason of the door opening 22, each of the door panels is substantially L-shaped or—more specifically—inverted L-shaped and comprises a vertically extending portion 23 and a horizontally extending lintel portion 24. In assembled position, the free ends 25 of the lintel portions 24 abut one another. If an open archway is desired, the door panels D may be used without additional trim. Alternatively, the door opening may be fitted with a conventional door frame. If desired, a pre-fabricated steel or wood door frame is placed between the two door panels which are then moved together so as to embrace the door frame.

The window panels W are also formed in pairs comprising panels W1 and W2 and are essentially the same as the basic panel B of Figure 1 except that each has an opening 27 which together form the window opening. Corresponding parts of the panel are designated by the same reference numerals as in Figure 1. By reason of the window opening, each of the window panels W is substantially C-shaped comprising a vertically extending

portion 28, a horizontally extending sill portion 29 and a parallel horizontal lintel portion 30. When the window panels are assembled, in the building, the free end edges of the sill portions and lintel portions abut one another in approximately the center of the window. Before the two panels are pushed together, a pre-fabricated window frame may be placed between them so as to fit into the window opening.

The manner in which the four basic panel shapes B, C, D and W are used in the construction of a building is illustrated in Figures 11 to 17. Figure 11 is an exploded view illustrating, by way of example, how the various panels are used. Figures 14 to 17 show, by way of example, the use of the panels in constructing a two-story building.

A poured concrete or other footing or foundation F is provided with a shoulder 31 (Figure 14) for supporting the joints 32 of the first floor 33. On its upper face, the foundation F is provided with tongues 34 and 35 which project upwardly from the foundation and may, for example, be formed of suitable strips, (Figures 12 and 13) embedded in the concrete of the foundation. The projecting portions of the tongues 34 and 35 correspond in cross-section with the grooves 5 in the bottoms of the panels. The foundation is also provided with a series of spaced wells 36 which extend down into the foundation, the spacing of the wells being equal to the width of the panels.

After the foundation has been completed, a plurality of panels are assembled on it in upright position. The grooves 5 in the lower edges of the panels fit over the tongues 34 and 35 of the foundation, thereby aligning the panels with the foundation and with one another. The vertical side edges 7 of adjacent panels abut one another so that the opposite channels 6 together form a vertical cylindrical hollow shaft. The panels are positioned so that the shaft formed by channels 6 are in alignment with the wells 36 in the foundation. Figure 11 illustrates the use of basic side panels B, a pair of door panels D, a corner panel C and a pair of window panels W. Each of the panels may either be one piece or may be in sections, as described above.

After the panels have been assembled on the foundation, a plurality of reinforcing bars, wires or rods are positioned in the shaft formed by channels 6 and in the trough 8 at the tops of the panels. Alternatively, the reinforcing rods as assembled concurrently with the assembling of the panels. As illustrated in Figure 2, there are a plurality of vertical reinforcing rods 38 in each of the shafts formed by the channels 6, the rods being held in position by tie wires 39. The reinforcing rods 38 extend down into the wells 36 in the foundation and in a multiple story building also extend into the aligned vertical shaft formed by the channels 6 in the vertical side edges of the next tier of panels. There are also a plurality of horizontally reinforcing rods 41 disposed in the troughs 8 provided at the upper edges of the panels. The reinforcing rods 41 extend continuously through the troughs of successive panels and are preferably connected with vertical reinforcing rods 38, for example by tie wires 42.

After the panels are assembled and the reinforcing rods are positioned as described, concrete is poured into the vertical shaft formed by the channels 6 and by the wells 36 in the foundation and also in the horizontal troughs 8 at the tops of the panels to provide an integral poured concrete skeleton or frame-work F comprising vertical pillars or columns 43 cast in place in the wells 36 and the shafts formed by the channels 6 and integral horizontal beams 44 cast in place in the trough 8. The reinforced columns and beams thus formed not only bind the panels together into an integrated structure but also constitute a strong structural framework or skeleton that carries the structural loads of the building, for example the load imposed by the ceiling, roof and any

upper story. Since the panels themselves provide complete forms for the poured concrete framework, the labor and material customarily required for erecting forms and subsequently removing them are eliminated. In erecting a multiple story building, the concrete of the framework is preferably poured after completing each tier of panels, i. e. after completing each story. As the reinforcing rods extend continuously from one story to the next and as the building can be erected so quickly that the concrete in the framework of one story is still green when that of the next story is poured, the result is an integral skeleton of framework for the whole building.

When the panels are provided with metal mesh 17, as described above, this mesh extends into the channels 6 and the trough 8 and the marginal portions of the mesh are hence embedded in the poured concrete pillars and beams of the building skeleton. An even stronger interlock is provided by bending the edge portions of the metal mesh to form hooks 45 (Figure 5) and passing a reinforcing rod similar to the rods 38 down between the overlapping hooked portions of adjacent panels so as to lock them together.

In a multiple story building, joists 47 which support the ceiling and the second floor extend through the notches 13 provided in the inner flanges 12 of the first tier of panels and the inner ends of the joists rest on the concrete beams 44 which constitute a portion of the structural skeleton of the building. The notches 13 not only position the joists correctly without measuring but also holds them in a vertical position. If desired, additional concrete can be poured into the troughs 8 between the ends of the joists so as to fill, or nearly fill, the troughs and thereby anchor the joists still more solidly.

After the joists 47 have been positioned in the notches 13 of the first tier of panels, a strip 48 (Figures 14 and 16) is secured in place across the ends of the joists in alignment with the tongues 34 and 35 of the foundation. A second tier of panels is then erected on top of the first tier, the grooves 5 in the lower edge of the panels fitting over the strip 48 to align the panels with each other and with those of the first tier. The inner and outer edges of the second tier of panels bear directly on the flange portions 11 and 12 of the lower panels. The panels thus provide a continuous wall surface, both inside and outside the building.

Additional stories are erected one after another in like manner until the desired height has been reached. It will be noted that, since the joists 47 rest on the concrete beams 44 of the integral concrete skeleton or framework, the floor loads are carried by this structural framework rather than by the panels. Hence, the panels can be formed of relatively lightweight material having inadequate strength to carry the building loads.

When the top story is reached, the joists 50 for the ceiling are inserted in the notches 13 of the upper tier of panels and the end portions bear on the horizontal beams 44, as described below. Rafters 51 for the roof overlap the ends of the joists 50 and extend through notches 14 in the outer flanges of the panels, the material which normally fills these notches having been cut or knocked out. Two small notches are cut in the lower edge of each rafter. A notch 52 fits over the bottom of the panel notch 14 in which the rafter rests. By reason of this notch, the rafter also rests on the concrete beam 44. A second notch 53 fits over the inner flange portion 12 of the panels. Because of the offsetting of the notches 13 and 14, as described above, the rafter comes down alongside the joist in overlapping relationship. The rafter is preferably secured to the end of the joist by means of nails, screws, bolts or other fastening means 54. The depth of the notch 14 in the outer flange portion of the panel and the notch 52 in the lower edge of the rafter is such that the upper edge of the rafter is substantially flush with the upper outside corner of the panel.

Hence, when the roofing 55 is secured on the upper side of the rafters, it is in engagement with the upper outside edges of the panels, thus forming a weatherproof and insectproof seal, thereby avoiding the necessity of having to fit sealing strips or pieces between the rafters. Through direct engagement of the rafters with the beam 44 and through connection of the rafters with the joist 50 which rest on this beam, the load of the roof is transmitted to the poured concrete framework of the building, thereby relieving the panels of this load.

After the walls are erected, a suitable finishing coat may, if desired, be applied to the inner and outer surfaces. For example, the outer surface may be stuccoed and the inner surface plastered. In this event, the stucco and plaster are applied directly to the panels, no studing, furring, plaster board or other intermediate structure being required. Alternatively, a suitable finishing coat can be incorporated in the manufacture of the panels or can be sprayed or brushed on after the panels have been erected. Because of their self-insulating properties, the panels need no additional insulating materials and preferably constitute substantially the entire wall segment.

Inside walls and partitions are constructed in like manner. The thickness of the wall is varied in accordance with proper architectural design. Ordinarily, the inner walls will be thinner than the exterior walls of the building. It will be recognized that, by reason of the versatility of the panels and the flexibility of design, any desired type of building can be erected, using only a relatively small number of different prefabricated panels. By reason of the way in which the panels fit together, a building can be erected with relatively unskilled labor, thereby reducing building costs still further. The construction in accordance with the invention thus provides great latitude in architectural design.

In speaking of like parts in the specification and claims, the term "like" is used in the sense of meaning either identical or similar. It will be understood that many modifications can be made in the details of construction. The invention is therefore not limited to the specific construction shown by way of example in the drawings.

What I claim and desire to secure by Letters Patent is:

- 45 1. In building construction having a ceiling, a foundation, a plurality of vertical panels of a height to extend from the foundation to the ceiling and of a lesser width than height, the meeting vertical edges of adjacent panels having like channels of semi-polygonal cross-section which together form a vertical shaft extending continuously from the foundation to the level of the ceiling, the foundation and the lower edges of the panels having interfitting portions for aligning the panels with the foundation and with each other, each of said panels having along its upper edge a trough and inner and outer flanges on opposite sides of the trough, said flanges forming continuations of the inner and outer surfaces of the panel respectively, the inner flange having a notch extending vertically downward from the upper edge of the flange to a level a substantial distance above the bottom of the trough, a poured concrete skeleton comprising concrete column portions cast in place in said shafts and extending continuously from the foundation to said troughs and continuous horizontal concrete beam portions cast in place in said troughs, and joists constituting part of the ceiling structure extending through the notches in the inner flanges of the panels and bearing on said beam portions, whereby the load of the ceiling is carried by said poured concrete skeleton, while said notches position the joists and restrain them from turning.
- 60 2. In building construction comprising a foundation, a ceiling and a roof, a plurality of vertical panels of a height to extend from the foundation to the ceiling and of a lesser width than height, the meeting vertical edges of adjacent panels having like channels of semi-polygonal cross-section which together form a vertical shaft extend-

ing continuously from the foundation to the level of the ceiling, the foundation and the lower edges of the panels having interfitting portions for aligning the panels with the foundation and with each other, each of said panels having along its upper edge a trough and inner and outer flanges on opposite sides of the trough, said flanges forming continuations of the inner and outer surfaces of the panel respectively, the inner and outer flanges having notches extending down from the upper edges thereof to a level above the bottom of the trough, the notches in the inner and outer flanges being offset so that their opposite side edges are in a common plane, a poured concrete skeleton comprising concrete column portions cast in place in said shafts and extending continuously from the foundation to said troughs and continuous horizontal concrete beam portions cast in place in said troughs, joists constituting part of the ceiling structure extending through the notches in the inner flanges of the panels and bearing on said beam portions, and rafters constituting part of the roof structure extending through the notches in the outer flanges of the panels and secured to the end portions of the joists, whereby the load of the ceiling and roof is carried by said poured concrete skeleton.

3. In multiple story building construction, a foundation having tongue portions projecting upwardly on the upper face thereof, a plurality of vertical wall panels of a height approximately equal to the first story ceiling height of the building and of a width less than the height, the meeting vertical edges of adjacent panels having like channels of semi-polygonal cross-section which together form a cylindrical shaft extending continuously from the foundation to the level of the first story ceiling, each of said panels having in its lower edge a groove fitting over the tongue portion of the foundation to position the panels relative to the foundation and each other and having along its upper edge a trough and inner and outer flanges on opposite sides of the trough, said flanges forming continuations of the inner and outer surfaces of the panel respectively, the inner flange having at least one notch extending vertically downward from the upper edge of the flange to a level a substantial distance above the bottom of the trough, a poured concrete skeleton comprising concrete column portions cast in place in said shafts and extending continuously from the foundation to said troughs and continuous horizontal concrete beam portions cast in place in said troughs, joists for the first story ceiling and second story floor extending through the notches in the inner flanges of the panels and bearing on said beam portions, tongue portions projecting upwardly above said joists, a second tier of like panels bearing on the inner and outer flanges of the lower panels and positioned by inter-engagement of said latter tongue portions with grooves in the lower edges of the upper panels to form a second story wall, and a continuation of said poured concrete skeleton comprising column and beam portions cast in place in the vertical shafts and horizontal troughs provided by the upper panels.

4. In a building construction having a foundation, a wall and a ceiling, a wall panel constituting a unit of said wall and having a height approximately equal to the vertical distance from the foundation to the ceiling, a width approximately one-fourth to one-half the height and a thickness substantially equal to the wall thickness of the building, said panel comprising a continuous inner wall portion, a continuous outer wall portion and integral peripheral and transverse web portions connecting said inner and outer wall portions and cooperating with them to form a plurality of closed hollow cavities between said wall portions, the peripheral web portion and adjacent peripheral portions of the inner and outer wall portions cooperating to form a groove extending along the bottom edge of the panel, a channel of semi-polygonal cross-section extending along each of the vertical side edges and a trough extending along the upper edge, the upper portions of the inner and outer wall portions forming

inner and outer flanges on opposite sides of said trough, the inner flange having at least one notch extending vertically downward from the upper edge of the flange to a level above the bottom of the trough.

- 5 5. In building construction having a ceiling, a foundation having a plurality of spaced wells and tongues projecting upwardly from the upper surface of the foundation between said wells, a plurality of wall members superposed on one another in vertical alignment, each of
10 said wall members having spaced parallel inner and outer wall portions and a continuous peripheral wall portion enclosing a sealed hollow space inside said member, each of said wall members other than the uppermost members having a peripherally extending groove in its lower peripheral wall portion, a peripherally extending tongue on its upper peripheral wall portion, and vertically extending channels in its opposite vertical peripheral wall portions and each of said uppermost wall members having a peripherally extending groove in its lower peripheral wall
15 portion and vertically extending channels in its opposite vertical peripheral wall portions, the inner and outer wall portions of said uppermost wall member projecting upwardly a substantial distance above the upper peripheral wall portion to provide an integral trough, at least the
20 inner wall portion of said uppermost wall member having in its upper edge spaced rectangular notches extending downwardly and terminating a substantial distance above the upper peripheral wall of said member, said wall members being assembled in tiers with the grooves in
25 the lower peripheral walls of the lowermost tier fitting over and interlocking with said tongues on the foundation and with side edges of the inner and outer wall portions of adjacent members abutting one another whereby said channels form vertically extending enclosures, said enclosures being aligned with said wells in the foundation and with the grooves in the lower peripheral wall portions of a superposed tier fitting over and interlocking with the tongues on the upper peripheral wall portions of the subjacent tier and with the vertical
30 side edges of inner and outer wall portions of adjacent members abutting one another and aligned with the vertical side edges of the subjacent wall members whereby said channels form vertically extending enclosures aligned with the enclosures between members of the subjacent tier,
35 the channels between adjacent wall members of the uppermost tier being in communication with said trough, concrete cast in place in said wells, channels and troughs bonding all of said members together and to the foundation and ceiling structural members extending through
40 said notches and supported by said concrete.
45 6. In a building construction having a ceiling, a foundation having a plurality of spaced wells and tongues projecting upwardly from the upper surface of the foundation between said wells, a plurality of wall panels each divided into a plurality of sections, disposed one above another, the width of said panels being equal to the center-to-center distance between said wells, each of said sections having spaced parallel inner and outer wall portions and a continuous peripheral wall portion enclosing
50 a sealed hollow space inside said member, each of said sections other than the uppermost section of each panel having a peripherally extending groove in its lower peripheral wall portion, a peripherally extending tongue on its upper peripheral wall portion and vertically extending channels in its opposite vertical peripheral wall portions, the uppermost section of each panel having a peripherally extending groove in its lower peripheral wall portion and vertically extending channels in its opposite vertical peripheral wall portions, the inner and outer wall portions of said uppermost section projecting upwardly a substantial distance above the upper peripheral wall portion to provide an integral trough, at least the inner portion of said uppermost wall member having in its upper edge spaced rectangular notches extending downwardly and
55 terminating a substantial distance above the upper peripheral wall portion of said uppermost section.

riperipheral wall of said member, said sections being assembled on said foundation with the grooves in the lower peripheral walls of the lowermost sections fitting over and interlocking with said tongues on the foundation and with the grooves in the lower peripheral walls of upper sections fitting over and interlocking with said tongues on the upper peripheral walls of lower sections, the side edges of the inner and outer walls of the sections of each panel being aligned with one another and abutting the side edges of the inner and outer walls of the adjacent panels to form vertically extending enclosures, said enclosures being aligned with said wells in the foundation, ceiling structural members having end portions extending through said notches and into said trough, and concrete cast in place in said wells, vertically extending enclosures and troughs of the assembled panels, bonding all of said sections together and to the foundation and providing concrete columns in said enclosures and an integral beam in said trough, the ends of said ceiling members being at least partially embedded in said beams and thereby anchored securely.
